UNITED STATES PATENT OFFICE.

ADDIS E. CHAMBERLAIN, OF CINCINNATI, OHIO, ASSIGNOR TO CHAMBERLAIN & CO., OF SAME PLACE.

IMPROVEMENT IN COOKING-STOVES.

Specification forming part of Letters Patent No. 42,432, dated April 19, 1864.

To all whom it may concern:

Be it known that I, ADDIS E. CHAMBERLAIN, of Cincinnati, Hamilton county, Ohio, have invented a new and useful Improvement in Cooking-Stoves; and I do hereby declare the following to be a full, clear, and exact description thereof, reference being had to the accompanying drawings, making part of this specification.

My improvement relates to an improved manner of applying and securing a deflecting plate or screen within the fire-chamber of a cooking-stove, as hereinafter described.

Figure 1 is a longitudinal section of the fire chamber and hearth of a stove provided with my improvement. Fig. 2 shows my screen detached from the stove. Fig. 3 represents the broiling-cover. Fig. 4 is a horizontal section through one end of my screen.

A, B, C, D, and E represent, respectively, the fire-chamber, the ash-pit, the top and front plates, and the sliding hearth of an ordinary cooking stove.

F represents my deflecting plate or screen, so fixed in the stove as to intervene between the fire and the fire-doors, and, by inclining inwardly toward its lower part, acting to lead the draft to the under side of the fire near its mid-width, the draft being in this way applied to the fire in the most efficient manner and the entrance of cold air direct to the flue prevented.

G G are wings, which, projecting forward from the ends of the plate F, flank the door opening on each side and shut out the external air.

An inwardly-projecting flange, H, at the bottom of the screen acts to stiffen the plate and to conduct the draft well to the middle of the fire.

The plate F is still further stiffened and protected from too direct contact of the fire by means of flatings I.

Beside the customary projections employed to confine stove-plates in their places, my plate F is additionally secured by means of ears J J', which are confined between the customary clamp-rods and the front plate, D. The plate F is perforated near its top and provided with a sliding register, K, which being opened, the effluvia of broiling is enabled to escape into the fire.

The register K may also be opened for the purpose of checking combustion.

L is a cover, which, being placed upon the hearth when the stove is being employed for broiling, serves to expedite the cooking action and to confine the effluvia. l are air-inelets in the cover L.

I claim herein as new and of my invention—

The deflecting plate or screen F, constructed as described, with cheeks G G', flange H, ears J J, and a register, K, the said screen being secured within the fire-chamber, as herein specified, and for the purposes set forth.

In testimony of which invention I hereunto set my hand.

A. E. CHAMBERLAIN.
